DEVICE FOR SUPPLYING A GREASY PACKING SUBSTANCE TO THE TIGHTENING SPACES OF DRY GAS HOLDERS

Konrad Jagschitz, Mainz, Germany, assignor to
 Maschinenfabrik Augsburg-Nürnberg A. G.,
 Nuremberg, Germany, a corporation of Germany

Application June 3, 1931, Serial No. 541,829
 In Germany June 14, 1930

9 Claims. (Cl. 48—176)

It is known in connection with dry or waterless gasholders (disk gasholders), to supply a greasy mass to the space between the wall of the gasholder and the disk (either such wall or the disk being movable and the other stationary) or such space being open towards the space enclosed by the gasholder wall, the grease forming a gas-tight packing between the latter and the said disk. In order to replace the grease that may have become lost during service a pump is provided by which the tightening space is re-filled with grease at certain intervals of time.

The present invention relates to a device by which the grease intended to replace that which has become lost during service is supplied automatically. According to the invention there is inserted an intermediate receiver into a pipe connecting the grease space with a pump driven, preferably, by an electromotor, such intermediate receiver having a variable space and being subjected to an exterior pressure, and the grease being supplied to the tightening place or places from such receiver as long as the pump is not running. And in order to replace the lost grease when the contents of said intermediate receiver has been consumed, a switch is provided for the motor driving the pump and is automatically actuated by means of a device connected with said receiver, the automatic action proceeding in such manner that the pump commences to supply grease as soon as the said receiver has become empty, and comes to a standstill when the receiver has been re-filled.

The invention is illustrated in the accompanying drawing on which is shown the interior of a waterless disk gas holder equipped with a device designed according to this invention, the holder being shown in vertical section and the inner parts being shown partly also in vertical section and partly in side view.

On the drawing, *a* denotes the flat, disk-shaped stationary bottom of the vertically movable bell *c*; the bottom *a* is supported by standards *b*. The gas is contained in the space above said bottom. The tightening between the bottom and the bell is effected chiefly by means of the grease that is contained in the annular space *e*. Such packings are known and I do not, therefore, claim them as my invention. The annular space *e* is formed on its outer side by the adjacent portion

of the inner surface of the bell; on its inner side by the adjacent portion of the wall *h* of a vessel *i*, on its top by a ring *g* and at its bottom by a ring *f*. The wall *h* consists of sheet-metal and is bendable, and it is bent by means of a liquid contained in the vessel *i*; this liquid can in winter-time be heated by a heating coil *k* to prevent freezing.

Introduction of the grease into the space *e* is effected by means of a pump *l* driven by an electromotor *m*. The pump draws the grease from a receptacle *n* through a pipe *o* and conveys it then through pipes *p* and *q* into the tightening space *e*. The pipe *q* consists of two parts, between which are inserted bellows *r*, the bottom *s* of which is subjected to the external pressure exerted by a weight *t* and transmitted to said bottom by a lever *x*. The bellows are filled with the grease and the latter is, therefore, also subjected to the pressure and is thereby forced into the space *e*, whereby the amount of grease which has become lost owing to the vertical movements of the bell is automatically replaced.

u denotes a vertically movable switch arranged in a conductor leading to the motor and by means of which the motor *m* can be switched on and off. The switch is guided by two sleeves and can be shifted in them by means of a bell-crank lever *v v'* in whose full line position the motor is switched off, whereas in the dotted line position of said lever the motor is switched on. The lever arm *v* is connected with the lever *x* by a rod *w*, and the position of the switch depends, therefore, upon the position of the bottom *s* of the bellows. When the bellows *r* have become practically empty, the switch has arrived in the position shown in dotted lines whereupon the motor is switched on and the pump commences to run so as to re-fill the bellows with grease from the receptacle *n*. When this has been accomplished, that is to say, when the bottom *s* has again arrived in its lowermost position, the lever *v* will have been turned by the lever *x* and the rod *w* to such an extent that it shifts the switch *u* into that position in which the motor circuit is broken, whereupon the pump will cease to run.

The top parts of the bellows and the bottom of the vessel *i* are in direct contact with one another or are made integral, and if the contents

of the vessel *i* is heated in winter-time by the heating coil *k* a part of the heat is transmitted to the grease in the upper portion of the bellows so that this portion remains sufficiently liquid 5 or mobile to enable it to be advanced by the bellows or pump pressure. A separate heating coil may be provided for the grease in the bellows.

If the gas holder is large, a plurality of devices of the above-described kind may be provided, so 10 that every portion of the correspondingly long seal can be provided with the packing grease. The several bellows may be connected with one another by pipes constituting a circular piping which may communicate with only one pump 15 that is common to all bellows. I wish it to be understood that in these respects a variety of constructional forms is possible without departing from the invention.

The places where the bellows communicate with 20 the two parts of the tube *q* may be opened and closed by means of valves *y* and *z* which are firmly connected with one another, as shown. The common valve-rod has two spaced abutment members which are alternately actuated by the 25 arm *v'* of the bell-crank lever. When these parts are in the full line position in which the bellows are completely filled with the grease and the motor circuit has been interrupted so that no more grease is fed into the bellows, the valve *z* is closed 30 and the valve *y* is open. The pressure exerted by the weight *t* drives the grease entirely into the tightening space *e*, not also in the direction to the pump. If, however, the lever *x* has drawn the lever *v* downwardly into the lowermost position 35 thereof, the lever arm *v'* will have shifted the common rod of the valves in such a direction that now the valve *z* is open and the valve *y* is closed so that the grease can be pumped into the bellows, but the pressure is not transmitted to the space *e*. It is, therefore, impossible 40 for the grease to be pressed out along the inner surface of the bell during the operation of the pump when the pressure is high, so that no grease is lost.

45 The described features, viz. the automatic supply of the packing grease, as well as the heating of the contents of the vessel *i* and of the bellows *r*, are requisite in view of the nature of the grease which is comparatively thick or solid and 50 does not, therefore, follow the hydraulic laws which are valid only for actual liquids, such as water, oil, and the like. Also the resistance arising in the pipes increases in the latter with grease far more than with actual liquids, especially 55 with the increase of the distance from the pump, and in view thereof it might occur that where the automatically acting shutting valves at the bellows or its equivalent are lacking, there the grease would be fed only into the first bellows and its appertaining tightening place at the bell, and would there escape, whereas the other bellows would receive too little or perhaps no grease. But owing to the provision of the valve 60 arrangement such detrimental effects are completely obviated. The heating coil likewise serves a novel function in view of the nature of the sealing material, as the heating prevents the grease in cold weather from becoming so stiff that the operativeness of the device might be 65 destroyed. There is obviously a material difference between this application of the heating device and the employment of the same in the known sealing devices where water or oil etc. 70 is used as packing substance, in that in the latter 75

case either the formation of ice is to be prevented or impure matter is to be separated.

I wish it to be understood that I do not limit myself to the details shown and described merely by way of example. Many departures in the details are possible without departing from the gist and essence of the invention as defined in the claims. Thus, for instance, instead of the bellows a cylinder with a piston therein may be used, and instead of the controlled valves controlled cocks or other equivalent members may be used.

I claim:

1. In a waterless gasholder, the combination of a closure disc and a gasholder section movable relatively to each other, a packing attached to said disc, mechanism for supplying a greasy packing substance to such packing comprising a grease supplying pump, a conduit leading from said pump to said packing, and an intermediate grease receiver inserted in said conduit and comprising a chamber of variable capacity through which the grease passes.

2. In a waterless gasholder, the combination of a closure disc and a gasholder section movable relatively to each other, a packing attached to said disc, mechanism for supplying a greasy packing substance to such packing comprising a grease supplying pump, an electromotor for driving said pump, a switch for switching said motor on and off, a conduit between said pump and said packing, an intermediate grease receiver inserted in said conduit and comprising a chamber of variable capacity through which the grease passes, and means for switching on said motor automatically when said receiver has become at least partially depleted, and for switching off the said motor when the said receiver has been refilled.

3. In a waterless gasholder, the combination of a closure disc and a gasholder section movable relatively to each other, a packing attached to said disc, mechanism for supplying a greasy packing substance to such packing, comprising a grease supplying pump, an electromotor for driving said pump, a switch for switching said motor on and off, a conduit between said pump and said packing, an intermediate receiver for the grease inserted in said conduit and comprising a chamber of variable capacity through which the grease passes, means for switching on said motor automatically when said receiver has become at least partially depleted, and for switching off the said motor when the said receiver has been refilled, shutting-off members for the inlet opening and the outlet opening of the receiver, and means for operating such members.

4. In a waterless gasholder, the combination of a closure disc and a gasholder section movable relatively to each other, a packing attached to said disc, mechanism for supplying a greasy packing substance to such packing, comprising a grease supplying pump, a conduit between said pump and said packing, an intermediate receiver inserted in said conduit and comprising a chamber of variable capacity through which the grease passes, and means for heating the said intermediate receiver.

5. In a waterless gasholder, the combination of a stationary disc, a movable bell positioned over said disc and movable with respect thereto, a packing between the edge of the disc and the interior wall of the bell, and mechanism for supplying a greasy packing substance to said packing, said mechanism comprising a grease supplying pump, a conduit leading from said pump to said

packing, and an intermediate grease receiver inserted in said conduit and comprising a chamber of variable capacity through which the grease passes.

5 6. A waterless gasholder as set forth in claim 5 including an electromotor for driving the grease pump, a switch controlling the circuit of said motor and means for closing said switch automatically when the receiver has become at least partially depleted and for opening said switch when the receiver has been refilled.

10 7. A waterless gasholder as set forth in claim 5 including an electromotor for driving the grease pump, a switch controlling the circuit of said motor and means for closing said switch automatically when the receiver has become at least par-

15 tially depleted and for opening said switch when the receiver has been refilled.

tially depleted and for opening said switch when the receiver has been refilled, said chamber of variable capacity including a movable wall, and said means including a lever movable in response to the movements of said wall.

8. A waterless gasholder as set forth in claim 5, including a motor for driving the pump, and means for closing the communication between the chamber of variable capacity and the pump when the motor is not in operation.

9. A waterless gasholder as set forth in claim 5 including a motor for driving the pump, and means for closing the communication between the chamber of variable capacity and the packing when the motor is set into operation.
